CLAIM

The ornamental design for a connector housing, as shown and described.

DESCRIPTION

FIG. 1 is a front perspective view of a connector housing showing our new design.

FIG. 2 is a rear perspective view thereof.

FIG. 3 is a top plan view thereof.

FIG. 4 is a bottom plan view thereof.

FIG. 5 is a side elevational view thereof.

FIG. 6 is another side elevational view thereof shown rotated 90 degrees from the view of FIG. 5.

FIG. 7 is another side elevational view thereof shown rotated 90 degrees from the view of FIG. 6; and,

FIG. 8 is another side elevational view thereof shown rotated 90 degrees from the view of FIG. 7.

The broken lines are for illustrative purposes only and form no part of the claimed design.
